HOUSING OF A LEAF MILL OR THE LIKE

Daniel C. Koturov, Sheboygan, Wis., assignor to
Gilson Bros. Co., Plymouth, Wis.

Filed Apr. 19, 1972, Ser. No. 245,685

Term of patent 14 years

Int. Cl. D15—03

U.S. Cl. D35—2 A

FIG. 1 is a perspective view of the housing, the intake chute being shown in an elevated position in this figure.

FIG. 2 is a perspective view of the housing, the intake chute being shown in its lowered position in this figure.

FIG. 3 is a side elevation of the housing with the chute in lowered position.

FIG. 4 is a rear elevation of the housing.

I claim:

The ornamental design for the housing of a leaf mill or the like, as shown.
